UNITED STATES PATENT OFFICE.

WALN WALDEN COFFEE, OF ATLANTA, GEORGIA.

ATTACHMENT FOR PLATEN-PRESSES.

1,355,753.

Specification of Letters Patent.

Patented Oct. 12, 1920.

Application filed June 30, 1920. Serial No. 392,933.

To all whom it may concern:

Be it known that I, WALN W. COFFEE, a citizen of the United States, and a resident of Atlanta, in the county of Fulton and 5 State of Georgia, have invented certain new and useful Improvements in Attachments for Platen-Presses, of which the following is a specification.

My invention is an improvement in attachments for platen presses, and has for its 10 object to provide an attachment of the character specified, especially adapted for use with platen presses equipped with Miller feeders for converting such presses into envelop presses.

In the drawings:

Figure 1 is a plan view of a portion of a platen press provided with the attachment.

Fig. 2 is a perspective view of the lower 20 end of one of the clips.

Fig. 3 is a similar view of the lower end of the other clip.

In the present embodiment of the invention a pair of clips 1 and 2 is provided 25 which are adapted to be arranged upon the platen 3 in spaced relation, being spaced apart slightly less than the length of the envelop. The clip 1 has two lugs 4 at one side edge, and one lug 5 at the other side edge, 30 and the clip 2 is similarly provided with lugs 6 and 7 similarly placed. These lugs are adapted to fit into slits 7 in the tympan to hold the clips in place, and each clip is provided at each inner end with means for 35 engaging above the envelop to position the same, and to hold it from off the platen so that the delivery fingers can get the envelops, the said envelop being indicated at 8.

The clip is provided at its inner end with 40 an upwardly offset integral tongue 9, which extends below the lower edge of the clip 1 as clearly shown, and is upwardly curved at its free end as indicated at 10. This tongue has a section 11 which is adjustably connected therewith, the body 9 of the tongue having over-lying flanges 12 forming guides at its upper end, in which the section 11 is

slidable. The clip 9 is provided with an upwardly offset portion 13 at its inner end, which portion extends beyond the lower end 50 of the clip as shown, and is bent upwardly as indicated at 14.

A series of quads or guide pins 15 is arranged between the clips at the upper end thereof, and the register fork 16 extends below the quads or guide pins. A pair of plates or bars 16 is arranged at the lower end of the platen, the free upper ends of the bars extending beneath the envelops when positioned as shown. These bars 16 are 60 hooked under the bail as shown, and extend just beneath the edge of the envelop to hold it lifted from the platen so that the delivery fingers can engage beneath the same.

I claim:

1. An attachment for platen presses for converting them into envelop presses, comprising a pair of clips having lugs for engaging slits in the tympan to hold the clips in place, said clips being adapted to be 70 spaced apart less than the length of an envelop, each clip having at its inner end an upwardly offset portion adapted to overlie envelops, each of the said portions having a tongue extending beyond the adjacent side 75 edge of the clip toward the delivery side of the platen, one of said clips having an extension tongue adjustably connected with the upwardly offset tongue and extending in the opposite direction.

2. An attachment for platen presses for converting them into envelop presses, comprising a pair of clips having lugs for engaging slits in the tympan to hold the clips in place, said clips being adapted to be 85 spaced apart less than the length of an envelop, each clip having at its inner end an upwardly offset portion adapted to overlie envelops, each of the said portions having a tongue extending beyond the adjacent side 90 edge of the clip toward the delivery side of the platen.

WALN WALDEN COFFEE.
